UNITED STATES PATENT OFFICE

ALFRED S. CALLAWAY, OF CHICAGO, ILLINOIS, ASSIGNOR TO THE KENDALL COMPANY, OF BOSTON, MASSACHUSETTS, A CORPORATION OF MASSACHUSETTS

ATHLETIC SUPPORTER

Application filed October 3, 1929. Serial No. 397,005.

This invention relates to improvements in athletic supporters and it consists of the matters hereinafter described and more particularly pointed out in the appended claims.

5 The primary object of the invention is to improve the manner of connecting the sack of a supporter of this kind to the waist band thereof in such a manner that the extensibility of the band in the vicinity of the 10 sack shall not be unduly impaired.

Another object of the invention is to provide a novel manner of connecting the ends of the waist band together in band form without the necessity of the usual attaching 15 strip, and to accomplish this object the associated ends of said band are overlapped with a portion of the sack disposed therebetween. The parts are held together by means which do not unduly impair the extensibility of the parts.

20 These objects of the invention as well as others together with the many advantages thereof will more fully appear as I proceed with my specification.

25 In the drawings:—

Fig. 1 is a perspective view of an athletic supporter embodying the preferred form of my invention.

Fig. 2 is a detail vertical sectional view 30 through the adjacent parts of the band and sack of the supporter on an enlarged scale, the plane of the section being indicated by the lines 2—2 of Fig. 1.

Fig. 3 is a view similar to Fig. 1 showing 35 the assembly of the parts before the final stitching together thereof.

Referring now in detail to that embodiment of the invention illustrated in the accompanying drawings, 1 indicates the waist 40 band of the supporter and 2—2 indicate the leg bands associated therewith, both made of an elastic webbing or other suitable material. The waist band is made from a length of such webbing greater than the 45 normal circumferential length thereof to provide end parts 3 and 4 adapted to overlap one another. The extremity of each end is cut on the bias in opposite directions and is folded inwardly to form hems 5—5. Said 50 two ends are then brought into overlapping

relation and are secured together as will soon appear.

6 indicates the sack of the supporter, which is preferably made of a strip of knitted fabric of such character that it is extensible and will stretch both longitudinally and laterally so that it will act for its intended purpose. The bottom of the sack is gathered to reduce its normal width and it is there suitably secured to the bottom ends of 55 the leg bands 2—2. The top ends of the leg bands are suitably secured to the waist band at the sides thereof in the manner well known.

The top end of the sack is turned over 60 upon itself to form a fold 7 and this fold is disposed upon or against the bottom marginal portion of the end 3 of the waist band as best shown in Fig. 3. The other end 4 is then disposed upon the first mentioned end 65 and above said fold 7 of the sack and the parts are then secured together by a line of elastic stitching 8 of the zigzag or German type. Other lines of similar stitching 9, 10 and 11 respectively are then employed 70 to secure the folded over ends 3 and 4 respectively to parts of the waist band as best shown in Fig. 1.

Thus as is apparent that part of the waist band at the front thereof is of a double 75 thickness and the fold at the top of the sack is disposed between the parts providing said double thickness. In this manner no raw or open edges of either waist band or sack are exposed so that a more neat appearance 80 is produced and the comfort of the wearer is thereby increased. By forming the ends 85 3 and 4 of the waist band on the bias as described, the liability of injuring the elastic strands of the waist band webbing in stitching them together, is greatly reduced. Again the ravelling of said ends before 90 forming of the folds thereon and subsequent stitching is eliminated.

95 While in describing my invention I have referred in detail to the form, arrangement and construction of the various parts thereof, the same is to be considered merely as illustrative so that I do not wish to be limited 100

thereto except as may be specifically set forth in the appended claims.

I claim as my invention:—

1. An athletic supporter embodying there-in an elastic waist band having biased ends 5 disposed in overlapping relation and secured by stitching parallel to said ends and formed to provide a part of a double thickness in said waist band of a greater length at the bottom than at the top of said waist band, 10 and a sack having a folded top margin disposed between said part of greater length of said double thickness and secured thereto by an elastic stitch.
2. An athletic supporter embodying there-in an elastic waist band having biased ends disposed in overlapping relation and secured by stitching parallel to said ends and formed 15 to provide a part of a double thickness in said waist band of a greater length at the bottom than at the top of said waist band, and a sack having a folded top margin disposed between said part of greater length of 20 said double thickness and secured thereto so that it is extensible therewith.

25 In testimony whereof, I have hereunto set my hand, this 26th day of September, 1929.

A. S. CALLAWAY.
